UNITED STATES PATENT OFFICE.

WILLIAM B. UPDEGRAFF, OF ELIZABETH, NEW JERSEY.

FLUID-PRESSURE PRESS.

Application filed February 27, 1926. Serial No. 91,124.

The object of my invention is to provide means for developing extremely high unit pressures on material to be subjected to pressure, such as is required for pressing master dies into blanks, in the manufacture of dies, as used by jewelers, etc.; for briquetting material confined between plungers in a suitable case, or female die; or for pressing material together between platens or plates, such as is common practice in the manufacturing arts. It is usual to employ for such purposes, presses operated by mechanical means, and also presses operated by pneumatic or hydraulic fluid pressure.

In mechanically operated presses, there are limits in pressure available for use, due to the safe bearing pressures which can be applied to journals, crank pins, eccentrics, pindle bearings, etc., also due to bending and deflection of crank shafts, eccentric shafts, etc. In the usual type of crank, eccentric, or pindle type mechanical presses, the pressure is not uniform through the entire working stroke, and this working stroke is necessarily comparatively short.

In presses actuated by air, water, or other fluid pressure, it is possible to apply, in existing types, fairly high unit pressure, and this pressure can be applied uniformly through any given length of stroke or travel of the moving member of the press. In existing types of hydraulic presses, the limitation of intensity of pressure is largely determined by the allowable intensity of the hydraulic or fluid pressure which can be exerted in the cylinder of the press. This limitation results from the inability of leather, hemp, or other packing, to confine the fluid in the cylinder, and yet permit of relative motion between the ram and cylinder. To increase the diameter or area of the hydraulic ram, necessitates increasing the lateral dimensions of the press, often to a prohibitive extent, and results in greatly increased weight and strength of platens, and consequently increased cost of press, and increased floor space, and usually results in increased deflection of platens, which is undesirable. Intensifying the unit hydraulic pressure, above that usually carried in accumulator systems, is likewise objectionable, owing to the increased cost, floor space, etc., and also because, by the use of an intensifier, to increase the accumulator pressure, the press ram stroke, or travel, is

definitely limited by the limit of volumetric displacement of the ram or plunger of the intensifier. A further, and very important factor, which prevents the use of extremely high unit hydraulic pressure, is the difficulty in making cylinders sufficiently strong to resist the bursting pressure exerted by the fluid; and also other difficulties, such as pump and valve troubles, etc.

My invention provides means whereby the unit pressure exerted by the platens of a hydraulic press, is practically doubled, without increasing the area of the platens, and without increasing the fluid pressure.

The improvement claimed is hereinafter fully set forth.

In the accompanying drawings: Figure 1 is a vertical central section, through a fluid pressure press, embodying my invention; Fig. 2, a view, in elevation, of the same, taken at a right angle to Fig. 1; Fig. 3, a plan or top view; and, Figs. 4 and 5, horizontal sections, on the lines *a a* and *b b*, respectively, of Fig. 1.

In the practice of my invention, referring descriptively to the specific embodiment thereof which is herein exemplified, a hydraulic cylinder, 1, fitted with a ram, 2, is mounted on, and abuts against, a stationary platen, 3, with which, if preferred, it may be cast integral. A fluid pressure pipe, 1^b, controlled, in the usual manner, by a valve or valves, (not shown), is connected to the cylinder, 1. The ram, 2, abuts against, and operates, a moving platen, 4, with which it may be formed integral, and the stationary platen, 3, is connected to another stationary platen, 5, located above it, by suitable tie rods, 8, or equivalent tension members. The structure above described, provided with the usual packings, fluid passages, valves, etc., is substantially similar to hydraulic die presses of the type heretofore known, and my invention combines with it the members which will now be described.

A cylinder, 1^a, of substantially similar construction to the cylinder, 1, is mounted on the upper platen, 5, and a ram, 2^a, is fitted in the cylinder, 1^a, a suitable stuffing box, or other packing member, being provided. The ram, 2^a, abuts against, or may be formed integral with, a yoke, 6, which is connected, by tension rods, 7, or equivalent members, to the lower movable platen, 4. The material to be pressed is inserted in the space which

intervenes between the movable platen, 4, and the fixed upper platen, 5; and the movable platen, 4, is pushed against the material by the lower ram, 2, and pulled, in the same direction, by the upper ram, 2^a, through the yoke, 6, and tension members, 7, the unit pressure exerted by the platens on the material to be pressed being thus practically double that which would be exerted under like conditions, by one cylinder only. A fluid pressure pipe, 1^c, is connected to the cylinder, 1^a, and the usual channels, valves, etc., for confining and controlling the supply and exhaust of fluid to and from the cylinder, which do not form part of my present invention, are not shown.

In the practical application of the invention, fluid pressure may be admitted to either cylinder primarily, or to both cylinders simultaneously, and the cylinders and rams may be of the same, or of different, diameters, and may be operated at the same, or at different, unit hydraulic pressures. Pull-back or pushback cylinders and rams, or any other suitable known means, may be applied, as desired, for opening the press after a pressure stroke has been made, that is to say, for separating the platens, 4 and 5, and in so doing, expelling the fluid from the cylinders, 1 and 1^a. Anvils, dies, or other auxiliary appliances, may be attached to the platens, 4 and 5, if desired, to concentrate and apply the pressure developed by the press cylinders, and through the rams, rods, platens, etc., to the material on which the application of pressure is desired.

I claim as my invention and desire to secure by Letters Patent:

1. In a fluid pressure press, a stationary platen, a platen movable toward and from said stationary platen, a fluid pressure cylinder disposed on the side of the stationary platen that is farthest away from the movable platen, a fluid pressure cylinder disposed on the side of the movable platen that is farthest away from the stationary platen, pistons in said cylinders, means operatively connecting said pistons to said movable platen, and means for exerting fluid pressure in said cylinders to produce simultaneous forces in the same directions acting on said movable platen.

2. In a fluid pressure press, a stationary platen, a platen movable toward and from

said stationary platen, a fluid pressure cylinder disposed on the side of the stationary platen that is farthest away from the movable platen, a fluid pressure cylinder disposed on the side of the movable platen that is farthest away from the stationary platen, tension members connecting said second cylinder and said stationary platen, pistons in said cylinders, means operatively connecting said pistons to said movable platen, and means for exerting fluid pressure in said cylinders to produce simultaneous forces in the same directions acting on said movable platen.

3. In a fluid pressure press, a stationary platen, a platen movable toward and from said stationary platen, a fluid pressure cylinder disposed on the side of the stationary platen that is farthest away from the movable platen, and adapted to exert thrust on said stationary platen, a fluid pressure cylinder disposed on the side of the movable platen that is farthest away from the stationary platen, tension members connecting said second cylinder and said stationary platen, pistons in said cylinders, means operatively connecting said pistons to said movable platen, and means for exerting fluid pressure in said cylinders to produce a simultaneous thrust in opposite directions on said stationary platen from said cylinders and from the engagement of the movable platen and the work.

4. In a fluid pressure press, a stationary platen, a platen movable toward and from said stationary platen, a fluid pressure cylinder and piston disposed on the side of the stationary platen that is farthest away from the movable platen, a fluid pressure cylinder disposed on the side of the movable platen that is farthest away from the stationary platen, a piston in said cylinder adapted to exert thrust on said movable platen, tension members operatively connecting the piston of said first cylinder to said movable platen, means for exerting fluid pressure in said first specified cylinder whereby the moving platen is pulled toward the stationary platen, and means for exerting fluid pressure in second specified cylinder, thereby exerting a thrust on said moving platen, tending to move it toward the stationary platen.

WILLIAM B. UPDEGRAFF.
